UNITED STATES PATENT OFFICE.

MORRIS KOHN, OF CHICAGO, ILLINOIS.

CLOTH-CUTTING MACHINE.

SPECIFICATION forming part of Letters Patent No. 425,102, dated April 8, 1890.

Application filed November 18, 1889. Serial No. 330,675. (No model.)

To all whom it may concern:

Be it known that I, MORRIS KOHN, a citizen of the United States, residing at Chicago, in the county of Cook and State of Illinois, 5 have invented a new and useful Improvement in Foot-Pieces for Cloth-Cutting Machines, of which the following is a specification.

This invention relates to the construction of the foot-piece attached to the cutting-heads of cloth-cutting machines, and whose function it is to pass under the pile of cloth and lift it from the table. As heretofore constructed, these foot-pieces have usually been made in one solid piece having no movement upon their supports; but in the application, Serial No. 308,590, filed by me on the 25th day of April, 1889, I show a lifting-foot provided with a forked device having its limbs located at either side of the disk-knife 10 and extending forward of the cutting-edge, with means for lifting the forward end of the fork device, so that the goods may be thereby raised and the cut made uniform throughout the entire height of the pile. The lifting device shown in said application performed its work very well; but it is nevertheless open to some objections. Being narrow, it applied lifting power to the goods only along a narrow line, and when working near the edge of 15 the pile it allowed the goods to slip laterally out of the way of the knife. It was also objectionable for other reasons. Instead of providing the foot with a narrow lifter, I now make the foot itself in two parts—a front 20 part and rear part, and hinge the front part to the rear part, and provide it with means whereby it may be raised to lift the goods. The goods are thus lifted by a broad lifter and supported to a considerable distance at 25 either side of the line of cutting, whereby any tendency of the goods to slip when in the lifted position is obviated.

The drawings show at Figure 1 a side elevation of the cutting-head of a cloth-cutting machine embodying my present invention. At Fig. 2 is shown a rear elevation of the foot 30 detached, and at Fig. 3 a plan of the same.

In said drawings, A represents the supporting-sleeve or housing of the cutter-head

covering and supporting the power-communicating parts of the machine. 50

a a are the gears carrying motion to the knife-disk B.

C D represent the foot, adjustably secured to the casing E by the screw e and arm e', 55 said casing being suspended from the housing A. As shown, the foot is made in two parts, the front part C having a rearward extension c and a slot c', which gives room to the knife. At d the front part is hinged, so 60 that it may be lifted to the position shown by the broken lines by appropriate means—such, for instance, as the jointed levers F f and the thumb-lever G, which latter is located in close proximity to the handle by 65 which the operator guides the cutting, the lower lever F being joined to the bent end g of the extension c. It will now be seen that if the lever G is depressed the movable part of the foot will be raised to the position 70 shown by the broken lines, or to any intermediate position, the intention being to give the movable part C such a range of movement as will insure the lifting of the lower layer of goods to the point where it will be cut by 75 the most advanced part of the knife. A spring H encircles the part f, and is employed to return the operating-levers to their normal position.

The construction shown provides a movable lifting device operable at will, having the slot which surrounds the knife closed at both ends, so that the sides of the lifter cannot spring or get out of position or get against the edge of the knife. This latter objection 80 was present in the forked lifter shown in my previous application.

I claim—

1. The combination, with the cutter and cutter-head of a cloth-cutting machine, of a 90 foot adapted to pass under the cloth and made in two parts—a forward hinged part C and a rear stationary part D—supports for said foot, and means for raising the forward part C to lift the goods, substantially as specified.

2. The combination, with a disk-cutter of a cloth-cutting machine, of a foot consisting of

a hinged part C and a support therefor, said part C being hinged to the support back of the cutter, and means for raising said part C, substantially as set forth.

5 3. The combination, with the disk-cutter of a cloth-cutting machine, of the foot consisting of the hinged part C and a support therefor, said part C being hinged to the sup-

port back of the cutter and having a slot therein, closed at both ends, to receive the cutter, and means for raising said part C, substantially as set forth. 10

MORRIS KOHN.
